UNITED STATES PATENT OFFICE

ANDREW H. BAKKEN, OF EDGEWOOD, PENNSYLVANIA, ASSIGNOR TO WESTINGHOUSE ELECTRIC & MANUFACTURING COMPANY, A CORPORATION OF PENNSYLVANIA

HINGED CLAMP FOR GAS OR LIQUID-PROOF HOUSINGS

Application filed November 6, 1928. Serial No. 317,623.

My invention relates to clamping devices and particularly to clamping devices for housings enclosing electrical apparatus and the like.

5 One object of my invention is to provide a clamping structure for a water-tight housing that shall be cheap to manufacture, simple to manipulate and integral with the housing to prevent loss or misplacement of the parts.

10 Another object of my invention is to provide a plurality of U-shaped clamps for a housing of the above-described type that shall be mounted on rods provided on the side of the housing, the clamps having apertures of greater diameter than the diameter of the said rod to permit pivotal and lateral movement thereon.

15 A still further object of my invention is to provide a plurality of C-clamps that shall be supported by means of a rod, through a large hole in each clamp, to a receptacle that has a cover hinged thereto, the parts of the hinge being like the clamp and rod being arranged to have considerable mechanical play so that both the clamps and the cover may be moved laterally after being moved into position.

20 With these and other objects in view, the invention comprises the novel structure, combination and arrangement of parts that will be herein fully pointed out in the following description, taken in conjunction with the drawing, in which;

25 Figure 1 is a side view, in elevation, of a structure embodying my invention.

30 Figs. 2 to 5 are enlarged views of sections of the structure shown in Fig. 1, disclosing the unique construction of my invention.

35 My invention comprises, in general, a submersible housing 1 including a receptacle 2 that is provided with mounting members 3 for supporting the receptacle 2 and the electrical apparatus mounted therein. A handle 4 is provided on the side of the receptacle 2 to be connected to the enclosed apparatus.

40 The handle is shown in three positions, the two broken-line outlines indicating the off and the on positions while the solid line out-

line indicates the neutral position of the contact members.

45 Terminals 5 are provided on the top and lower sides of the receptacle 2 to provide insulated water-tight connections for the circuit to the enclosed apparatus. 55

50 A cover 6 is supported on the receptacle 2 by a pair of hinges 7, one of which is shown in Fig. 3. The butt members of said hinges 7 are similar to the members 8 shown in Fig. 60 1, except that the last-mentioned members are not united to form a hinge but are employed as guide members to position the cover on the receptacle when moved into closed position. The hinged members 7 are 65 illustrated in Fig. 1 as if located on the remote side of the receptacle 2, but whenever it is advantageous to have the cover open with an opposite movement, the pins of the hinges 7 may be changed to the members 8, whereupon the butts of the present hinges 7 will 70 function merely as guide members.

75 The receptacle 2 and the cover 6 are made of sheet material, welded at their seams to form water-tight joints. Their abutting faces are formed into flanges 9 and 11 between which a packing 12 is employed to form a seal.

80 In order to provide a simple and efficient clamping system for the flanges 9 and 11, I have devised the novel C-clamp that will now be described. A rod 13 is provided, along each side of the flange 9, and this is employed to attach my clamping members to the housing in such a way that they cannot be clamped 85 in skewed position on the housing. The attachment just referred to insures that the clamps will never become detached and lost when the receptacle is opened for inspection. The C-clamp 14 comprises a U-shaped member 15, one end of which has a clamping face 16 and a hole 17 of larger diameter than the rod 13 that passes therethrough. The opposite side of the U-shaped member 15 is provided with a threaded hole for the reception 90 of an adjustable screw 18.

95 In order to space my clamps 14 evenly along the flanges 9 and 11 and retain them in their predetermined positions, I provide a plurality of cylinders or tubes 19 which

slide over the rods 13 when the clamps 14 are assembled. It is desirable to have the end clamps on each of the four sides of the cover 6 located as near to the corners of the latter as possible. Such positioning of the clamps is shown in Figs. 2 and 3 in which the clamps 14 are located immediately adjacent to the inner corners of the housing.

My C-clamp is particularly novel in that 10 it is supported on the rod 13 in such manner as to permit an angular movement of the C-clamp as well as a lateral movement thereon without increasing the force exerted on the rod 13 beyond that necessary for supporting the plurality of C-clamps. This arrangement permits the C-clamps 14 to be so moved back away from the flanges 9 and 11 that the cover 6 may be opened readily. When the cover 6 is again moved to its closed 20 position, the clamps 14 are turned to permit the screws 18 and the clamping faces 16 to slide into engagement with flanges 9 and 11. When the screws 18 are screwed down against the flange 11, the contacting face 16 is moved 25 upward into engagement with flange 9. Such an arrangement provides a large clamping area for the surfaces 9 and 11, thus ensuring a uniform pressure on the packing 12. It will be noted that, if the clamps 14 were so 30 closely fitted on the rod 13 that faces 16 did not bear on flange 9, pressure could only be transmitted to the flange 9 through rod 13 and its end bearings. To provide the necessary strength and rigidity for this purpose, 35 very bulky and clumsy construction would be necessary.

It will thus be seen that I have provided a novel arrangement for making a submersible housing water-tight by providing a receptacle with a cover that may be hinged from 40 either of its sides in such manner as to permit angular and lateral movement thereof and, at the same time, to provide members for guiding the cover to its closed position.

45 I do not wish to be restricted to the specific arrangement of the part herein set forth, as various modifications thereof may be effected without departing from the spirit and scope of my invention. I desire, therefore, that 50 only such limitations shall be imposed upon my invention as are indicated in the appended claims.

I claim as my invention:

55 1. A housing comprising a receptacle and a cover, a rod associated with the receptacle, a plurality of clamps having holes of greater diameter therein than that of said rod by which said clamps are supported to permit angular and lateral movement on said rod, 60 an extension on each end of each clamp, the one extension having an engaging face, the other an adjustable screw, said face and said screw being adapted to clamp said cover to said receptacle, whereby the turning of the 65 screw is adapted to draw said engaging face

against said housing without applying a lateral force to said rod.

2. A housing for electrical apparatus including a receptacle and a cover, a plurality of clamps associated with the abutting edges 70 of said receptacle and said cover, a rod for supporting the clamps and extending through holes therein, a plurality of spacers on the rod distributed between the clamps to retain them in predetermined spaced relation.

3. A housing for electrical apparatus including a receptacle and a cover, hinges for uniting the cover to the receptacle, a plurality of clamps retained by rods about, and positioned to engage, abutting flanges of the said 75 receptacle and cover, the said clamps being also mounted for angular and lateral movement.

4. A housing for electrical apparatus including a receptacle and a cover united by 80 hinges constructed to permit angular and lateral movement of the cover, a plurality of clamps retained by rods and supported to engage abutting flanges of the said receptacle 85 and said cover, the said clamps being also mounted for angular and lateral movement and means for spacing the clamps a predetermined amount, including a plurality of cylindrical members supported on said rods between the clamps.

5. An enclosing structure comprising a receptacle and a cover, hinges uniting the receptacle and cover along one side thereof in such manner as to permit the angular and lateral movement of the cover, a plurality of clamping members mounted along each side 90 of the structure and a single member on each of the sides for supporting the respective plurality of clamping members.

6. An enclosing structure comprising a receptacle and a cover, hinges uniting the receptacle and cover along one side thereof in such manner as to permit the angular and lateral movement of the cover, clamping members provided on each side of said structure and removable supporting means for 95 said clamping members.

7. An enclosing structure comprising a receptacle and a cover, hinges uniting the receptacle and cover along one side thereof in such manner as to permit the angular and lateral movement of the cover, clamping members provided on each side of said structure and removable supporting means for retaining the clamping members in a predetermined position on said structure.

In testimony whereof, I have hereunto subscribed my name this 26th day of October, 1928.

ANDREW H. BAKKEN. 125
